(57) **CLAIM**

The ornamental design for a device interface, as shown and described.

DESCRIPTION

FIG. 1 is a right-front perspective view of a device interface showing the new design;

FIG. 2 is a top view thereof;

FIG. 3 is a front view thereof;

FIG. 4 is a left side view thereof; and,

FIG. 5 is a right side view thereof.

The broken lines showing in FIGS. 1-5 are for illustrative purposes only and form no part of the claimed design.

1 Claim, 5 Drawing Sheets

FIG. 1

FIG. 2

FIG. 3

FIG. 4

FIG. 5
